LIPSTICK HOLDER

Giuseppe Russo, New York, N. Y.

Application June 6, 1945, Serial No. 597,881

2 Claims. (Cl. 206—46)

1

This is an invention of a lipstick applicator and of a package therefor and of a method of packaging said applicator.

The principal object of the invention is the provision of a handy disposable lipstick applicator carrying sufficient lipstick for a single application and having the means for sharply outlining the areas to which the lipstick is applied. The lipstick applicator herein described and claimed may be used in place of a lipstick brush for all the purposes for which such brush is normally used. Since the claimed lipstick applicator is intended to be used for a single application only, its hygienic advantages over a lipstick brush are obvious.

Another object is the provision of a method of making the lipstick applicator and packaging it in the handy package herein described.

A further object is the provision of a handy package for a plurality of lipstick applicators adapted to preserve the lipstick in fresh, usable condition for an indefinite period of time.

These and other objects are illustrated in the accompanying drawing in which—

Fig. 1 is a perspective view of a closed package in accordance with the present invention showing the lipstick applicators herein claimed inserted therein;

Fig. 2 is a view similar to that of Fig. 1 showing the package open;

Fig. 3 is a vertical section on the line 3—3 of Fig. 1;

Fig. 4 is a view of the lipstick applicator shown in Fig. 3;

Fig. 5 is a fragmentary horizontal section on the line 5—5 of Fig. 1;

Figs. 6, 7, 8, 9, 10 and 11 show the different successive steps in applying the lipstick to the applicator and sealing the latter in a moisture-proof container;

Fig. 12 shows in vertical section another type of moisture-proof container;

Fig. 13 shows a lipstick applicator sealed into said container; and

Fig. 14 shows the applicator before it has been sealed into the container.

The lipstick applicator 20 best shown in Fig. 4 comprises a round stick 21 having a tapered or pointed end 22 coated with a predetermined measure of lipstick compound or other cosmetic 23 in the form of a drop or ball. The stick 21 may be made of wood or other suitable material such as rolled Cellophane or fibrous material. It will be noted that the pointed end is provided with a rounded point rather than with a sharp

2

point. It is this rounded point that is used to define or outline the area to which the lipstick is applied. It is sufficiently pointed for this purpose but at the same time sufficiently rounded to permit of gentle application to sensitive skin areas.

Applicator 20 is packed in a tubular container 30 which may be made of fibrous or other suitable material. The manner in which this is done 10 and the manner in which the applicator is tipped with lipstick compound may be described as follows:

The pointed stick 21 is inserted into the tube 30 as shown in Fig. 6, the pointed end 22 protruding through the bottom of the tube. A coat 15 of wax 31 is then applied to said pointed end as well as to the area adjacent the pointed end as by dipping, the coated portion being shown in Fig. 7. The wax tip which covers the tip of the pointed end 22 is now broken away to expose the latter. This is shown in Fig. 8. The lipstick compound now is applied to the exposed tip of pointed end 22, also as by dipping. The result of this step is shown in Fig. 9.

Now the applicator 20 is complete and it remains to seal the same into the tubular container 30. It will be remembered that only the tip of the wax coat was removed, leaving a ring of wax around the stick 21 in the vicinity of the pointed

end 22. The stick 20 is now drawn back through the tube 30 until the lipstick coated end thereof is entirely enclosed by said tube. The ring of wax contacts the inner wall of the tube and serves to guide the stick therethrough, thereby preventing the tip of lipstick from rubbing against said wall. The wax ring also serves, once the stick is retracted to the position shown in Fig. 10, as a seal between the stick and the tube to prevent air from entering the tube therethrough and drying out the lipstick compound. The tube is itself now dipped into wax to seal off the lower opening thereof. A seal 32 of wax is thereby formed in the lower end of said tube as appears in Fig. 11.

The lipstick coated end of the individual applicator is now completely encased in an airtight container thereby preserving the lipstick compound for an indefinite period of time.

In the finished package, a plurality of applicators are carried in a corresponding number of tubular containers in a folder 40. Said folder 50 comprises a single sheet of heavy paper or cardboard or other suitable material, which is bent at its center portion to U-shaped form in cross section, the arms of said U-shaped portion extending up as high as the tubular containers 30 are

long, the folder being again bent or scored at the top of the U-shaped portion to provide a hinge construction, said folder being further bent or turned at the top to form a pair of arc-shaped portions in cross-section which engage and lock each other.

The tubular containers 30 containing the sealed-in applicators are placed in close order between, and affixed to, a pair of sheet members 41 of approximately the same height as the containers are long, and hence of approximately the same height as the arms of the U-shaped portion of the folder 40. These sheet members hold the tubular containers together. The unit formed thereby is placed between and affixed to the arms of said U-shaped folder portion as is shown in Figs. 1 to 3 and 5.

The folder shown in the drawing is intended to be affixed to the tubular containers 30 by means of an adhesive or in any other conventional manner. It is clear that a folder of the character described may be made in the form of a permanent accessory such as a compact or cigarette case. The use of such permanent folder would mean that tubular containers 30 would be brought together in the form of a refill to be carried in said folder and to be discarded in favor of another refill when the first is exhausted.

The device is now ready for use. The package which is carried in the purse in closed condition as shown in Fig. 1, is opened to the position shown in Fig. 2. One of the applicators is withdrawn from its container, the ring or band of wax surrounding it guiding it out of said container to prevent contact of the lipstick against the inner wall of the container. The applicator thus withdrawn is used in the usual manner and then discarded. The folder is again closed and returned to the purse for future use.

Another method of preparing and packaging the applicator is illustrated in Figs. 12, 13 and 14. The tubular container 30 is lined with a thin layer 50 of wax. This is done by dipping or spraying or in any other suitable manner. The lined tube is shown in Fig. 12. The applicator 20 is prepared by simply applying a tip 23 of lipstick compound to the pointed end 22 of the stick 21. The finished product is shown in Fig. 14. The applicator is now inserted into the wax lined tube as shown in Fig. 13 and the lower end of the tube is then dipped into wax to provide a bottom seal 32. The wax lining on the inner wall of the tube contacts the stick 21 and provides the necessary seal there.

Although the present invention has been described in connection with lipstick compound, it is clear that any type of cosmetic may be used which is capable of holding its shape.

I claim:

1. A cosmetic applicator sealed in an airtight container therefor, said applicator comprising a stick having a reduced, tapered rounded end, a

ring of wax formed on said stick adjacent said tapered rounded end, a tapered rounded tip of cosmetic affixed to the tapered, rounded end of the stick, the outer dimensions of said tip of cosmetic being smaller than the outer dimensions of the wax ring, said airtight container comprising a tube whose inside dimensions are slightly smaller than the outside dimensions of the wax ring but which are larger than the outside dimensions of the cosmetic tip, said stick being mounted in said container, the cosmetic tip end of said stick being inside the container and the opposite end of said stick extending outside thereof, a press fit being provided between the wax ring and the inside wall of the container, the opposite end of the container adjacent the cosmetic tip end of the stick being sealed off with wax, the cosmetic tip on said stick being free from contact with the inner wall of the container.

2. A cosmetic applicator sealed in its own individual airtight container, said applicator comprising a round stick having a reduced, rounded tapered point tipped with a cosmetic, said stick having a wax ring formed around it adjacent its tapered point, the outer diameter of said wax ring being greater than the outer diameter of the cosmetic tip, said cosmetic-tipped end of the stick being mounted within its said container, said container comprising a tubular member which is sealed off with wax at one end and which is open at the other end to provide ingress or egress for the cosmetic-tipped stick, said wax ring on the stick being sufficiently large to provide a seal between said stick and the inner wall of said tubular container, said wax ring being also sufficiently large to space the cosmetic tip on said stick from the inner wall of the tubular container and to provide a bearing on which said stick may be moved into and out of said container and preventing contact from being made between the cosmetic tip and the inner wall of the container.

GIUSEPPE RUSSO.
